UNITED STATES PATENT OFFICE.

BOLESLAW TURYNOWICZ, OF BOSTON, MASSACHUSETTS.

WASHHANGER.

1,278,261.

Specification of Letters Patent. Patented Sept. 10, 1918.

Application filed June 8, 1918. Serial No. 238,843.

To all whom it may concern:

Be it known that I, BOLESLAW TURYNOWICZ, a citizen of Russia, residing at Boston, county of Suffolk, Massachusetts, have invented certain new and useful Improvements in Washhangers, of which the following is a specification.

This invention relates to improvements in means for suspending lines or cords used 10 to display laundried articles while being dried.

The principal object of the invention is to provide means by which the line or cord may be maintained at all times in a proper 15 taut condition.

A further object is to provide means whereby the line may be inclined at an angle when it is desired to attach or remove articles thereon, and finally, to provide 20 means which may be readily attached to common supports such as are employed.

These and other like objects are attained by the novel construction and combination 25 of parts hereinafter described and shown in the accompanying drawings, forming a material part of this disclosure, and in which:—

Figure 1 is a side elevational view indicating the attachment of the line to its 30 supports.

Fig. 2 is a perspective view, showing the means for attaching the operating lever to some portion of the window or door frame from which the clothing is to be extended.

Fig. 3 is a side elevational view, showing the gears as attached to the operating lever; and

Fig. 4 is a fragmentary sectional view, showing the arrangement of gears attached 40 to the operating lever.

In Fig. 1 a window or door frame is indicated by the numeral 10, while a supporting post or mast is designated by the numeral 11. Attached to the mast, at a proper 45 height, is a fixed bracket 14 having pivoted in it a bell-crank lever, one arm 15 of which has secured to it a weight 16, while the other arm 17 carries at its end an eye 18, engaging a pulley 19, over which runs the line or 50 cord 20. This cord passes over a corresponding pulley 21 fixed by a pivoted link 22 to the bent end 23 of a lever bar 25, pivoted near its center to a bracket 28, the opposite end of the lever having an actuating handle 29 by which it may be operated.

The bracket 28 is here shown to consist

of a piece of angle iron provided with a plurality of openings 32 receptive of screws or similar fastening means by which it is secured to the frame of the window 10. 60

Secured to one of the limbs of the bracket 28 by rivets 34 is an arm 35, extending outwardly, forming a spindle 36, upon which the bar 25 is pivoted, held by the enlarged head 37. 65

Rigidly engaged upon the spindle 36 is a spur gear 38, meshing with pinions 40, pivoted upon spindles 41, having enlarged heads 42, which extends through the lever 25, the opposite ends of the spindles being 70 provided with annular heads 43, one of which is adapted to move in a track-way 44, formed in the surface of the bracket 28, while the other may enter a recess 45 also formed in the bracket and acting as a stop, 75 preventing further rotation of the bar 25 on which the pinions are mounted.

Secured upon the upper edge of the bar 25, by the screws 47 is a wire 48, bent outward and upward, forming a loop 49, the 80 reentrantly turned end of the loop being extended transversely on the bar 25, and adapted to enter either of the openings 52 and 53, formed in the face of the gear 38, thus locking it so that the lever 25 may be 85 held either horizontally or vertically, the detent end 50 of the wire being held normally in engagement due to the pressure of a flat spring 54 affixed upon the upper surface of the lever 25 by the screws 56. 90

In operation, the parts being assembled as shown in the full lines of Fig. 1, the cord will obviously be held taut, due to the weight on the bell-crank lever 15.

When it is desired to remove the articles, 95 the handle 29 is turned up, bringing the bar 25 into a substantially vertical position, as shown by the dotted lines, the bar being locked in position by the entry of the detent wire 50 into the opening 52, formed in the 100 gear 38, while obviously, when the detent is entered into the opening 53, the bar will be held vertical, thus stressing the cord.

Having thus described my invention what I claim as new and desire to secure by Letters Patent, is—

1. In a wash line support, the combination with two supports and a bracket engaged upon one support, of a bell-crank lever pivoted to the other support, a weight 110 engaged with one arm of said bell-crank lever whereby the other end is held nor-

2
mally perpendicular, a lever pivoted to said bracket, and means for holding said lever either horizontally or vertically.

2. In a wash line support, the combination with two supports, of a bracket secured upon one support, a bell-crank lever pivoted in said bracket, a weighted arm formed with said bell-crank lever, a second bracket on the other support, a manually operable lever fulcrumed near its center

upon said second bracket, a line extended from one of the ends of said bell-crank lever to the lower end of said manually operable lever, and means for locking said manually operable lever in either of two 15 adjusted positions.

In testimony whereof I have affixed my signature.

BOLESLAW TURYNOWICZ.

Copies of this patent may be obtained for five cents each, by addressing the "Commissioner of Patents, Washington, D. C."
